WINE RACK

Maxwell Bentley, 1331 Newbridge Road,
North Bellmore, N.Y. 11710

Filed May 22, 1972, Ser. No. 255,964

Term of patent 14 years

Int. Cl. D6—04

U.S. Cl. D7—71

FIG. 1

FIG. 3

FIG. 1 is a front top perspective view of a wine rack embodying my new design, the bottom being identical;

FIG. 2 is a rear elevational view thereof; and

FIG. 3 is a side elevational view thereof, the opposite side being identical.

I claim:

The ornamental design for a wine rack, as shown and described.
